UNITED STATES PATENT OFFICE

99,190

DESIGN FOR A TUBE CUTTER

August C. Dobrick, Chicago, Ill., assignor to The Imperial Brass Manufacturing Company, Chicago, Ill.

Application December 16, 1935, Serial No. 60,093

Term of patent 14 years

To all whom it may concern:

Be it known that I, August C. Dobrick, a citizen of the United States, residing at 5898 North Harlem Avenue, Chicago, in the county of Cook and State of Illinois, have invented a new, original, and ornamental Design for a Tube Cutter, of which the following is a specification, reference being had to the accompanying drawing, forming part thereof.

Figure 1 shows a back view and Figure 2 shows a side view of the tube cutter showing my new design.

I claim:

The ornamental design for a tube cutter, as shown.

AUGUST C. DOBRICK.
